UNITED STATES PATENT OFFICE.

BAXTER M. ASLAKSON, OF SALEM, OHIO.

GAS-ENGINE.

968,636.

Specification of Letters Patent. Patented Aug. 30, 1910.

Application filed October 14, 1907. Serial No. 897,414.

To all whom it may concern:

Be it known that I, BAXTER M. ASLAKSON, a citizen of the United States, and a resident of Salem, in the county of Columbiana and 5 State of Ohio, have invented certain new and useful Improvements in Gas-Engines, of which the following is a specification.

My invention relates to gas engines and particularly to the construction of the cylinders and their particular relation in the 10 engine.

The object of my invention is to provide a cylinder casing having cylinders therein which are removable and which are cast to 15 present ports for communicating with ports in the casing.

My invention is clearly set forth in the subsequent detailed description and illustrated in the accompanying drawings, in 20 which latter,

Figure 1, is a longitudinal sectional view through the casing and cylinders of a gas engine, and illustrating a preferred form of my invention. Fig. 2, is a longitudinal sectional view through the cylinder casing. Figs. 3 and 4, are longitudinal sectional views of the cylinders which fit in the upper bore of the casing and into which the gases are first admitted from the casing. Figs. 5 25 and 6, are longitudinal sectional views of the cylinders which have the exhaust ports located therein. Fig. 7, is an end view of the casing viewed from the left. Fig. 8, is a cross sectional view through the casing and 30 cylinders on line $x-x$ of Fig. 1.

A, indicates the casing, which is provided with air inlet chambers a , a , which are annular in form and extend around the cylinders, in open communication with the cylinder 35 inlet ports B' . A', is also an annular chamber through which the gas flows on its way to the interior of the cylinders B, by way of ports B^2 . The cylinders B and C are provided with flanged shoulders C' , which abut the casing ends, which ends are machined to present smooth faces, and the cylinders B, having been forced by pressure 40 into their proper positions in the casing and fitting the bores or bearing surfaces A^2 tightly to effect a fluid tight joint, and contribute to provide chambers D—D to serve 45 as water jackets. These cylinders may be removed when worn and new ones substituted. The ports B^2 are formed by notching 50 the inner end of a cylinder as illustrated,

thus permitting the projecting parts to serve in holding the piston rings from expanding when passing the inner ends of the cylinders.

It will be noted that the metal on line 60 Z—Z (Fig. 2) of the casing A, is free to expand longitudinally without bringing any strain on the cylinders, and that the cylinders may expand and contract independent 65 of the casing. The cylinders C, are provided with ports C^2 , through which the gas is exhausted. These cylinders are provided with heads E, which may be duplicates of each other, and which heads are bolted through the cylinder flanges to the casing 70 A. The cylinder heads have openings E' , through which the piston rods F, and tail rods G, may pass, suitable stuffing boxes H, being in co-relation to said openings. Said heads contain water jacket chambers I. 75 Passageways J, are formed in the heads to establish communication between the respective ends of the adjacent cylinders. Between and parallel with the tail rods G, is a guide rod K, which is supported at one end 80 by a projection L, cast on the contiguous cylinder head, and at the other end by the frame M, which is bolted to said head. The piston rods are connected to a combined 85 yoke and cross head at one end and the tail rods G are connected by a yoke at the other end which is guided by the guide rod K. Flanges N, (Figs. 7 and 8), are provided for the casing A, by means of which the casing may be firmly secured to the engine 90 frame work. Pistons O, operate, one in the upper cylinder and one in the lower cylinder, and serve as valves which control the inlet and exhaust ports.

In operation, assuming the pistons to be 95 in the position shown, the burned gases have just exhausted through ports C^2 to the atmosphere and scavenging air has been admitted through ports B' and followed by gas entering through ports B^2 . The pistons, 100 traveling to the right, close the ports, compress the gases which are burned to produce power on the return stroke, the pistons having passed over and uncovered the left hand series of ports a and gas ports 105 B^2 , thus exhausting the gases burned in the left hand end of the cylinders, and receiving its new charge of gas for the next power stroke in this end of the cylinders. 110 The general construction and operation of

this engine will be described and claimed in another application for patent, so that further description herein is not deemed necessary.

5 The chest P, has flanges whereby it can be conveniently bolted in position on the casing A, and said chest contains a central compartment P', and compartments P², P², at either side of the compartment P', said 10 compartments being in communicating relation with the air and gas ports a, A', in the casing, to convey air and gas under pressure thereto.

Having thus described my invention, what 15 I claim as new and desire to secure by Letters Patent, is,

1. A casing provided with separate air and gas ports, two independent cylinders detachably arranged end to end therein and 20 having ports which register with the air ports, one of said cylinders also having recesses notched therein at its inner end and forming gas ports which register with the gas ports in the casing.

25 2. A casing provided with separate air and gas ports, a plurality of independent cylinders therein arranged end to end and having ports for registering with the air ports, one of said cylinders also having recesses notched therein at its inner end and 30 forming gas ports which register with the gas port of the casing, said casing and cylinders forming water chambers.

3. A casing provided with ports and having 35 two bores side by side and faced ends, independent cylinders in said bores arranged end to end in pairs and having ports registering with said casing ports, each cylinder having a flange abutting against the 40 face of the casing, a head at each end having a flange abutting against the cylinder

flanges, and bolts holding said head and cylinder flanges to the casing.

4. A casing provided with ports and having two bores side by side, independent cylinders in said bores arranged end to end in pairs and forming the working cylinders of the engine and having ports registering with the ports in the casing and co-acting with the casing to form water chambers, a cylinder head at each end of the casing, each head having an open communicating passage between the working cylinders, a piston in each working cylinder having a piston rod and a tail rod which extend through the respective cylinder heads, a yoke connecting said tail rods and a guide for said yoke.

5. An engine comprising a cross head, a casing provided with ports and having two bores side by side, independent cylinders in said bores arranged end to end in pairs and forming the working cylinders of the engine and having ports registering with the ports in the casing and co-acting with the casing to form water chambers, a cylinder head at each end of the casing, each head having an open communicating passage between the working cylinders, a piston in each working cylinder having a piston rod and a tail rod which extend through the respective cylinder heads, a yoke connecting said tail rods, a guide for said yoke and said piston rods being connected to said cross head.

Signed at Salem in the county of Colum- 75 biana and State of Ohio this 16th day of September A. D. 1907.

BAXTER M. ASLAKSON.
